UNITED STATES PATENT OFFICE

FRANK J. ZIELINSKI, OF TORONTO, OHIO

ROLLING MILL

Application filed February 24, 1930. Serial No. 430,980.

This invention relates to rolling mills and has special reference to a mill for rolling packs of sheets such as are called planished iron and Russia iron.

5 More particularly the invention relates to sheet handling mechanism for rolling mills.

One important object of the present invention is to provide an improved and novel general construction of mechanism whereby 10 packs of sheets may be handled at a pair of rolls with a minimum of labor and with great efficiency.

A second important object of the invention is to provide, in such a device, a novel 15 means for evening the sheets in the pile or pack being handled.

A third important object of the invention is to provide improved means in connection with such pack handling mechanism for separating the sheets in a pack if such sheets 20 become stuck together.

A fourth important object of the invention is to provide an improved gripping device for such a mechanism, the device being arranged 25 to automatically grip the sheet pack on its return over the rolls.

A fifth important object of the invention is to provide an improved arrangement of pack gripper and means to reciprocate the same to 30 cause the gripper to deliver a pack to the rolls, rise over the rolls and grasp the returning pack and draw it back ready for the next pass.

With the above and other objects in view 35 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

45 Figure 1 is a plan view of a pair of rolls having the invention associated therewith.

Figure 2 is a section on the line 2—2 of Figure 1.

50 Figure 3 is an enlarged section on the line 3—3 of Figure 1.

Figure 4 is a section on the line 4—4 of Figure 3.

Figure 5 is a section on the line 5—5 of Figure 1.

Figure 6 is a detail elevation of the guide 55 for the pack and its support.

Figure 7 is an enlarged plan view of the gripper.

Figure 8 is a section on the line 8—8 of Figure 7 showing the gripper closed. 60

Figure 9 is a view similar to Figure 8 but showing the gripper open.

Figure 10 is a detail section on the line 10—10 of Figure 1.

Figure 11 is a detail end elevation of the 65 evener mechanism.

Figure 12 is a section on the line 12—12 of Figure 11.

Figure 13 is a section on the line 13—13 of Figure 11. 70

Figure 14 is a section on the line 14—14 of Figure 11.

Figure 15 is a section on the line 15—15 of Figure 11.

Figure 16 is a plan view of a portion of 75 the gripper carrying chain showing the method of attaching the gripper thereto.

Figure 17 is a section on the line 17—17 of Figure 16.

Figure 18 is a section on the line 18—18 of 80 Figure 3.

In the embodiment of the invention here shown there is disclosed a conventional pair of roll housings 10 supporting a pair of rolls 11. These parts are those common in 85 all such devices and are not, in their specific construction, any part of this invention, no changes or alterations being made therein except to provide necessary bolt holes or other means for securing the invention proper in 90 position. Such rolls being old and very well known, it is not deemed necessary to describe the same or their driving means in detail.

In front of the rolls is positioned a base plate 12 and across the front of said rolls extends a supporting bar 13 having its ends firmly fixed to the housings 10. At the end of this base 12 remote from the rolls is a pair of standards 14 and extending forwardly 95 from these standards are longitudinal bars 100

or rails 15 which have their forward ends supported on the cross bar 13 and bevelled as shown in Figure 5 to fit closely to the lower roll, 11. Adjacent the rolls these bars are 5 provided with suitable bearings to receive a rock shaft 16 to which is fixed a depending rock arm 17 slotted at its lower end to receive a pin 18 projecting from the forward part of a push bar 19 mounted on antifriction rollers 20 so that an operator, by pushing 10 this bar with his foot, may rock the shaft 16. Tilting bars 21 are fixed on the shaft 16 just outside the rails 15. Each of these bars is secured intermediate its ends to the shaft so 15 that it has a forward end normally projecting toward the space between the rolls while its rear end, provided with rollers 22, extends away from the rolls. Normally these bars lie in the full line position of Figure 5 but, to return the sheets over the top roll, are 20 tilted by the action of the foot bar 19 to the dotted line position of that figure. There is also fixed centrally of the shaft 16 a tilting arm 23 which projects toward the rolls and 25 has an upwardly facing channel 24 in its forward part for purposes presently to be described.

To the rear of the rolls 11 is positioned a cross bar 25 which has its ends secured to 30 the housings 10. Rails 26 have their forward ends supported on this cross bar and extend rearwardly and upwardly from the cross bar to a rear frame 27 which carries their rear ends. These rails are provided with anti-friction rollers 28. The upper side portions 35 of the frame 27 are connected to the housings 10 by side plates 29 having their lower edges provided with inwardly extending flanges 30. From a point adjacent the housings these 40 flanges extend rearwardly in parallelism to the rails 26 but forwardly and between the housings 10 these flanges are reversely curved to arch over the upper roll 11 as can clearly be seen in Figure 2. Each of the plates 29 thus extends forwardly of the rolls 11 and 45 each of said plates has mounted on its upper forward portion a sprocket wheel 31. A shaft 32 is journaled in the frame 27 and bridges the space between the plates 29. On 50 this shaft are fixed the sprockets 33 which are connected by loose chains 34 to the wheels 31 respectively. A motor 35 of the reversible multispeed type drives the shaft 32 and is provided with any suitable means (not 55 shown) for controlling its speed and direction of movement. Idlers 36 serve to keep the chains 34 from jumping the sprockets. Two opposite links of these chains 29 are provided each with an inwardly extending lug 60 37 to which is bolted the respective end of a gripper cross bar 38 supporting the gripper indicated in general in Figure 1 at 38 and specifically illustrated in Figures 7, 8 and 9. As there shown the bar 38 has mounted centrally 65 of its underside a guide member 39,

the opening of which extends transversely of the bar to accommodate a lower gripper jaw 40. A cooperating upper gripper jaw 41 has its rear end hinged to the jaw 40 and extends over the bar 38 toward the rolls 11. These jaws are so formed that, forwardly of the bar 38, they converge so that forward movement of the bar 38 relatively to said jaws will spread them open as in Figure 9 while rearward movement of said bar will, if no sheets are interposed between the jaws, allow them 70 to come together as in Figure 8. A bolt 42 extends upwardly from the jaw 40 through the jaw 41 and carries on its upper end a heavy compression spring 43 the tension of which may be regulated by a nut 44. This spring urges the jaws to closed or gripping position. While here shown as a single bolt and spring it is obvious that two or more such bolts and springs may be provided and 75 that the bolt and spring shown are indicative generically of a suitable means for urging the jaws to closed position. Secured on the jaw 41 just to the rear of the bar 38 is a hinge or pivot plate 45 whereto is pivoted and L-shaped dog 46 having its free end extending downwardly through an opening 47 in the jaw 41 so that it may enter a recess 48 in the bar 38 to hold said bar in jaw 80 opening position as shown in Figure 9. An arm 49 extends upwardly from the pivot end of this dog and is pressed by a suitable spring 50 to make certain the engagement of the dog in the recess 48 at the proper time in the operation. Across the rear end of the jaw 40 85 extends a cross bar 51 and springs 52 of the coiled tension type each having one end connected to the bar 51 and the other end connected to the bar 38 so that these springs constantly urge the bar to gripping position. A 90 hinge plate 53 is fixed forwardly of the bar 38 to the under side of the jaw 40 and a trigger 54 has its lower end pivoted to the plate 53 and extends upwardly through openings 55 in the jaws 40 and 41 to project above the latter. A spring 56 is connected to the upper end of this trigger and urges the trigger forwardly. A trip rod or bar 57 has its forward end pivoted to the upper end of this trigger and, at its rear end, engages the arm 49 so that rearward movement of the trigger 95 releases the dog and allows the bar 38 to move rearwardly relative to the jaws whereby the jaws may close and grip a plate or bundle or stack of plates. 100

In the operation of the device as thus far described we may suppose that a stack of plates has just passed forwardly between the rolls and is resting on the tilting arms with the latter in their normal or horizontal position. The operator in front of the rolls then tilts the arms as in dotted lines in Figure 5 and, with his tongs, starts the pack or pile of sheets up the arms. At the same time the motor is started to bring the gripper, which 105 110 115 120 125 120

is open, forward over the top roll and let its lower jaw rest in the channel 24. As the pack engages the trigger the dog is released and the gripper jaws close on the pack. The 5 motor is now reversed and the pack moved rearwardly over the top roll until it drops on the bed rails 26 whereupon the motor is thrown into forward position so that the pack, engaged by the gripper, is forced forward to be engaged by the revolving rolls. Meanwhile the front operator has restored the tilting arms 21 to normal position. Upon 10 the rolls gripping well on the pack the motor is speeded up which forces the bar 15 forwardly faster than the pack is moving through the rolls. This causes the jaws to open and release the pack. The motor is now slowed down and the dog catches the recess 48, the latter being elongated to give 20 the dog time to drop. This leaves the jaws open so that further forward movement of the gripper to carry it up and over the top roll places it in position again to receive and grip the pack. A guide 58 is slidably 25 mounted on the left hand end of the shaft 16 and is held in adjusted position by set screw 59. A bracket 60 is mounted on the front of the right hand housing 10 and through this bracket slides an evener or jogger arm 30 61 secured in adjusted position by a set bolt 62. Pivoted between its ends to the inner end of the evener arm is an oscillatable evener 63 having its upper end urged outwardly by a spring 64. On the inner face of 35 the lower end of this evener is a wear and adjusting plate 65 which may be adjusted in or out by a screw 66. A bent lever 67 is pivoted on the base 12 and has one end engaged against the plate 65 while its other 40 end is engaged by a rock arm 68 depending from the shaft 16. By this means one or more blows of the upper end of the evener lever 63 may be given the pack as it is raised from horizontal to return position, it being 45 merely necessary to tilt the tilting arms 21 up and down the desired number of times.

At the left side the rail 15 has its forward end higher than the rear, an inclined surface 50 69 being provided between the two. The rail 15 at the right side is slotted and a bar 70 (see Fig. 3) is slidably mounted on this rail and is held in position by a bolt 71 passing through a downwardly extending leg 72. The forward end of the bar 70 is bifurcated and a pack opener lever 73 is pivoted 55 in this bifurcated end and is connected by a link 74 with a double ended treadle 75 pivoted intermediate its ends to the lower end of the leg 72. The bar 70 is provided with a downwardly and rearwardly inclined surface at 60 its forward end and just above the rail 15 this end of the bar or slide is notched. The surface of the opener lever is correspondingly curved but its rear end extends across 65 the notches of the bar to normally close the

same. In case it is desired to open the pack it is merely necessary to raise the front end of the opener lever a small amount as the pack passes through the rolls whereupon the lower sheets will enter the notch while the upper sheets will be split off by the action of the opener lever. 70

From the foregoing it will be seen that the hand operations heretofore common in rolling sheets in packs have been almost entirely replaced by mechanical operations. 75

There has thus been provided a simple and efficient device of the kind described and for the purpose specified.

It is obvious that minor changes may be 80 made in the form and construction of the invention without departing from the material spirit thereof. It is not, therefore, desired to confine the invention to the exact form herein shown and described, but it is 85 desired to include all such as properly come within the scope claimed.

Having thus described the invention, what is claimed as new is:

1. In a plate handling attachment for a 90 pair of rolls, a set of tilttable arms positioned at one side of the rolls to receive plates passing from said rolls and movable to direct the plates over said rolls, a reciprocable gripper arranged to grasp the plates carried by the arms and draw them over said rolls, and guide means for said gripper arranged to guide the gripper toward the rolls in a path to deliver plates between said rolls and to further guide the gripper over the top of said 100 rolls.

2. In a plate handling attachment for a 105 pair of rolls, a set of tilttable arms positioned at one side of the rolls to receive plates passing from said rolls and movable to direct the plates over said rolls, a reciprocable gripper arranged to grasp the plates carried by the arms and draw them over said rolls, means to hold said gripper open to receive said plates, means urging said gripper to close, 110 and a tripping device for releasing the first mentioned means and positioned to be engaged for actuation by the plates entering the gripper.

3. In a plate handling attachment for a 115 pair of rolls, a set of tilttable arms positioned at one side of the rolls to receive plates passing from said rolls and movable to direct the plates over said rolls, a reciprocable gripper 120 arranged to grasp the plates carried by the arms and draw them over said rolls, guide means for said gripper arranged to guide the gripper toward the rolls in a path to deliver plates between said rolls and to further guide the gripper over the top of said rolls, means to hold said gripper open to receive said plates, means urging said gripper to close, 125 and a tripping device for releasing the first mentioned means and positioned to be 130

engaged for actuation by the plates entering the gripper.

4. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, means to hold said gripper open to receive said plates, means urging said gripper to close, a tripping device for releasing the first mentioned means and positioned to be engaged for actuation by the plates entering the gripper, and means for reciprocating the gripper adapted to effect opening of the gripper upon engagement of the plates between the rolls.
5. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, guide means for said gripper arranged to guide the gripper toward the rolls in a path to deliver plates between said rolls and to further guide the gripper over the top of said rolls, means to hold said gripper open to receive said plates, means urging said gripper to close, a tripping device for releasing the first mentioned means and positioned to be engaged for actuation by the plates entering the gripper, and means for reciprocating the gripper adapted to effect opening of the gripper upon engagement of the plates between the rolls.

6. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a guide at one side of the arms, and a jogger at the other side of the arms arranged to strike the lateral edges of the plates and drive them toward said guide.

7. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, guide means for said gripper arranged to guide the gripper toward the rolls in a path to deliver plates between said rolls and to further guide the gripper over the top of said rolls, a guide at one side of the arms, and a jogger at the other side of the arms arranged to strike the lateral edges of the plates and drive them toward said guide.

8. In a plate handling attachment for a pair of rolls, a set of tiltable arms positioned

at one side of the rolls to receive plates passing from said rolls and movable to direct the plates over said rolls, a reciprocable gripper arranged to grasp the plates carried by the arms and draw them over said rolls, means to hold said gripper open to receive said plates, means urging said gripper to close, a tripping device for releasing the first mentioned means and positioned to be engaged for actuation by the plates entering the gripper, a guide at one side of the arms, and a jogger at the other side of the arms arranged to strike the lateral edges of the plates and drive them toward said guide.

9. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, guide means for said gripper arranged to guide the gripper toward the rolls in a path to deliver plates between said rolls and to further guide the gripper over the top of said rolls, means to hold said gripper open to receive said plates, means urging said gripper to close, a tripping device for releasing the first mentioned means and positioned to be engaged for actuation by the plates entering the gripper, a guide at one side of the arms, and a jogger at the other side of the arms arranged to strike the lateral edges of the plates and drive them toward said guide.

10. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, means to hold said gripper open to receive said plates, means urging said gripper to close, a tripping device for releasing the first mentioned means and positioned to be engaged for actuation by the plates entering the gripper, and means for reciprocating the gripper adapted to effect opening of the gripper upon engagement of the plates between the rolls, a guide at one side of the arms, and a jogger at the other side of the arms arranged to strike the lateral edges of the plates and drive them toward said guide.

11. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, guide means for said gripper arranged to guide the gripper toward the rolls in a path to deliver plates between said rolls and to further guide the gripper over the top of said rolls, means to hold said gripper open to receive said

- plates, means urging said gripper to close, a tripping device for releasing the first mentioned means and positioned to be engaged for actuation by the plates entering the gripper, means for reciprocating the gripper adapted to effect opening of the gripper upon engagement of the plates between the rolls, a guide at one side of the arms, and a jogger at the other side of the arms arranged to strike the lateral edges of the plates and drive them toward said guide.
12. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a guide at one side of the arms, a jogger at the other side of the arms arranged to strike the lateral edges of the plates and drive them toward said guide, and an operative connection between the jogger and arms and arranged to actuate the jogger upon tilting of said arms.
13. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a guide at one side of the arms, a jogger at the other side of the arms arranged to strike the lateral edges of the plates and drive them toward said guide, an operative connection between the jogger and arms and arranged to actuate the jogger upon tilting of said arms, and foot operated means for tilting the arms and thereby actuating the jogger.
14. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, and a pack opener adjacent the rear ends of said arms.
15. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, and a pack opener adjacent the rear ends of said arms and including a tiltable lever movable between pack opening and inactive positions.
16. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a pack

opener adjacent the rear ends of said arms, said opener being adjustably movable toward and from said rolls, and means to secure the opener in adjusted position.

17. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a pack opener adjacent the rear ends of said arms and including a tiltable lever movable between pack opening and inactive positions, said opener being adjustably movable toward and from said rolls, and means to secure the opener in adjusted position, said pack opener including also an operating pedal movable therewith toward and from the rolls.

18. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a guide at one side of the arms, a jogger at the other side of the arms arranged to strike the lateral edges of the plates and drive them toward said guide, and a pack opener adjacent the rear ends of said arms.

19. In a plate handling attachment for a pair of rolls, a set of tiltable arms positioned at one side of the rolls to receive plates passing from said rolls and movable to direct the plates over said rolls, a reciprocable gripper arranged to grasp the plates carried by the arms and draw them over said rolls, a guide at one side of the arms, a jogger at the other side of the arms arranged to strike the lateral edges of the plates and drive them toward said guide, an operative connection between the jogger and arms and arranged to actuate the jogger upon tilting of said arms, and a pack opener adjacent the rear ends of said arms.

In testimony whereof I affix my signature.
FRANK J. ZIELINSKI.
